FIG. 1 is a perspective view of an electric heating integrated furnace showing our new design;

See application file for complete search history.

FIG. 2 is a perspective view thereof in an open state;

(56) References Cited

FIG. 3 is a front view in a closed state;

U.S. PATENT DOCUMENTS

FIG. 4 is a back view thereof;

D560,417 S * 1/2008 Ho D7/334
D601,378 S * 10/2009 Chung D7/334
D843,772 S * 3/2019 Wong D7/334

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of FIG. 1;

FIG. 10 is another enlarged view of FIG. 1; and,

FIG. 11 is an enlarged view of FIG. 3.

The broken lines shown on the drawings depict portions of the electric heating integrated furnace that form no part of the claimed design.
